UNITED STATES PATENT OFFICE.

CHARLES D. FRAUNFELTER, OF ZANESVILLE, OHIO, ASSIGNOR TO FRAUNFELTER CHINA COMPANY, OF ZANESVILLE, OHIO, A CORPORATION OF MAINE.

DESIGN FOR A CHINA PLATE OR SIMILAR ARTICLE.

Application filed June 18, 1925. Serial No. 13,810. Term of patent 7 years.

To all whom it may concern:

Be it known that I, CHARLES D. FRAUNFELTER, a citizen of the United States, residing at Zanesville, in the county of Muskingum and State of Ohio, have invented a new, original, and ornamental Design for a China Plate or Similar Article, of which the following is a specification, reference being had to the accompanying drawing, forming part thereof, and which shows a plan view of the new design for a plate, the ornamental border shown being repeated throughout the circumference of the plate.

I claim:

The ornamental design for a china plate or similar article as shown.

CHARLES D. FRAUNFELTER.
